UNITED STATES PATENT OFFICE.

LOUIS J. LARSEN, OF LONG ISLAND CITY, NEW YORK.

HEADPIECE FOR SAILS.

Application filed February 4, 1925. Serial No. 6,677.

To all whom it may concern:

Be it known that I, LOUIS J. LARSEN, a subject of the King of Denmark, residing at Long Island City, county of Queens, and

5 State of New York, have invented certain new and useful Improvements in Headpieces for Sails, of which the following is a specification.

This invention relates to improvements 10 in rigging for sailing vessels, and has particular reference to a head piece for sails.

In the use of Marconi or jib headed sails it has heretofore been customary to form a head piece made of wood to which the head 15 of the sail is secured by stitching. It has been found that these stitches become worn and break very quickly due to the handling of the sail, thus necessitating frequent repairs.

20 An object of the present invention is to provide an improved head piece for sails so constructed that the use of stitches to secure the head of the sail thereto is avoided and which may be readily and quickly attached to and detached from the sail.

Another object is to securely connect the 25 mast rope to the head piece in such manner that said rope will afford a means for preventing longitudinal movement of the head piece relative to the upper edge of the head of the sail and consequent accidental detachment of said head piece from the sail.

A further object is to so construct the head piece that when the sail stretches the 35 slack along the leach thereof may be taken up by an adjustment of the head piece relative to the halyard connected thereto.

The above and other objects will appear 40 more clearly from the following detailed description, when taken in connection with the accompanying drawing, which illustrates a preferred embodiment of the inventive idea.

In the drawing—

45 Figure 1 is a side elevation, partly broken away and shown in section, of the head piece showing the same in operative position;

Figure 2 is a section on the line 2—2 of 50 Figure 1; and

Figure 3 is a section on the line 3—3 of Figure 1.

The head piece of the present invention is particularly designed for use in connection with Marconi or jib headed sails, but

it is to be expressly understood that the invention is in no way limited to such use, the scope of the invention being defined by the appended claims.

The head piece of the present invention 60 is preferably made of metal and of a configuration similar to that of head pieces now generally employed, the same having a straight edge and a curved edge. The device is designed for attachment to the 65 head portion 4 of a sail 5 and to this end the straight edge of the body of the head piece is formed throughout its length with a longitudinally extending channel 6 and a restricted slot 7 communicating therewith. 70 When attaching the head piece to the sail the head portion of the latter is folded upon itself and the folds are stitched, as indicated at 8, so as to provide a permanent loop. The retaining element or rod 9 of a length 75 equal to that of the straight edge of the body of the head piece is inserted between the folds of the head portion 4 and engaged with the material of the sail at the end of the fold remote from the stitching 8. 80

One end of the rod 9 and the portion of the material of the sail adjacent thereto is then inserted into one end of the channel 6 with the portion of the folded material adjacent the rod 9 engaged in and projecting from the slot 7, as shown in Figure 2. The head piece is then moved longitudinally until the entire rod 9 is disposed within said channel. In this manner it will be apparent that the 85 head piece will be securely connected to the sail and that only a longitudinal movement of said head piece relative to the upper edge 90 of the sail will be possible.

The curved edge of the head piece is 95 formed throughout its length with a groove 11 for receiving the mast rope 12 secured to the luff of the sail and to the upper end of the leach thereof in the customary manner. When the mast rope 12 is in position the same forms a closure for the ends of 100 the channel 6 and prevents relative longitudinal movement between the head piece and the upper edge of the head portion of the sail.

In order to secure the mast rope in position so that the same will effectively act as a closure for the ends of the channel 6 the opposed faces of the head piece are provided with recesses 13 and in the corners of said 105 recesses adjacent the ends of the straight 110

edge of the head piece the latter is provided with openings 14 arranged adjacent the inner ends of openings 15 extending outwardly in diverging relation through the adjacent 5 wall of the recesses. Through the openings 14 and 15 there is extended a flexible element 16 which embraces the mast rope 12 and the ends of said element 16 are tied together, as indicated at 17, to securely retain the mast 10 rope in position in the groove 11. By securing each element 16 in position in this manner it will be obvious that only that portion of the element which extends about the exposed surface of the mast rope 12 will be 15 subject to wear occasioned by the handling of the sails, the remaining portion of the elements 16 being recessed within the head piece and disposed entirely within the planes of the outer opposed surfaces of said body. 20 In order to compensate for stretching of the sails the head piece is provided with a plurality of apertures 18 arranged at intervals adjacent the curved edge of the head piece and any one of which may be utilized 25 for the purpose of attaching the head piece to a halyard 19. With the halyard connected through the aperture shown at the left in Figure 1, the straight edge of said head piece will assume a substantially horizontal 30 position, but should the sail become stretched, as for instance, along its leach, this stretching may be taken up by connecting the halyard to either one of the other apertures 18 and by reason of the angular 35 relation of the halyard to the head piece it will be obvious that its connection to the head piece through either of the last named apertures will cause said piece to assume different angular positions with respect to 40 the horizontal. Thus, for example, in taking up the stretch along the leach of the sail, if the halyard is connected to the head piece through the aperture 18 at the right of Figure 1, the result will be a lifting of the right 45 hand end of the head piece, thereby compensating for the stretching which has occurred.

What is claimed is:

1. A head piece for sails formed from a single piece of material and including a body 50 provided with a channel for receiving a portion of a sail, and a rigid element engageable with said portion and capable of being mounted within said channel to prevent detachment of said sail from said body.
- 55 2. A head piece for sails formed from a single piece of material and including a body having a channel formed along one edge thereof and capable of receiving a portion of a sail, and a rod insertable into said channel and engageable with said portion for preventing detachment of said sail from said body.
- 60 65 3. A head piece for sails, including a body having a channel therein capable of receiving a folded portion of the sail, and means

insertable into said channel and between the folds of said portion to prevent detachment of said sail from the body.

4. The combination with a sail capable of having a portion folded over upon itself, 70 and a retaining element insertable between the folds of said portion; of a head piece having means for receiving said retaining element and the portion of said folds between which said element is inserted. 75

5. The combination with a sail capable of having a portion folded over upon itself, and a retaining element insertable between the folds of said portion; of a head piece having a channel and communicating slot 80 in one edge capable of receiving said retaining element and the portion of said folds surrounding said element, said folds extending through said slot.

6. A head piece for sails including a body having a channel therein capable of receiving a portion of a sail, and means insertable into said channel and engageable with said portion for preventing detachment of the sail from the body, said body having means for permitting the attachment of a mast rope thereto so that said mast rope will form a closure for the ends of said channel to prevent longitudinal movement therein of the first named means. 90 95

7. The combination with a sail capable of having a portion folded over upon itself, and a retaining element insertable between the folds of said portion; of a head piece having means for receiving said retaining element and the portion of said folds between which said element is inserted, and a mast rope secured to said body and forming a closure for the ends of said channel to prevent longitudinal movement therein of said retaining element and portion of said folds. 100 105

8. A head piece for sails, including a body having a channel formed along the entire length of one edge thereof, and a restricted slot communicating with said channel, said channel and slot being capable of receiving a portion of a sail, and means engageable with said portion and insertable into said channel to attach said body to said sail. 110

9. A head piece for sails, including a body having a channel formed along the entire length of one edge thereof, and a restricted slot communicating with said channel, said channel and slot being capable of receiving a portion of a sail, and a retaining rod engageable with said portion and insertable into and extending the length of said channel. 115 120

10. A head piece for sails, including a body having a channel formed along the entire length of one edge thereof, and a restricted slot communicating with said channel, said channel and slot being capable of receiving a portion of a sail, a retaining rod engageable with said portion and insertable 125 130

into and extending the length of said channel, and a mast rope secured to said body and forming a closure for the ends of said channel to prevent longitudinal movement 5 therein of said retaining rod and portion of said sail.

11. A head piece for sails including a body having recesses in opposed faces thereof and a channel extending along one of its 10 edges for receiving a portion of a sail, means to retain said portion in said channel, a mast rope extending along the other edge of said body, and means extending through the walls of said recesses and faces of said body 15 and embracing said mast rope, said means lying entirely within the planes of the outer opposed surfaces of said body, and said mast rope forming a closure for the ends of said channel.
12. A head piece for sails including a body having recesses in opposed faces thereof and a channel extending along one of its 20

edges for receiving a portion of a sail, means to retain said portion in said channel, a mast rope extending along the other edge of said body, means extending through the walls of said recesses and faces of said body 25 and embracing said mast rope, said means lying entirely within the planes of the outer opposed surfaces of said body, and said mast rope forming a closure for the ends of said channel.

13. A head piece for sails having a body provided with means permitting of attaching of the head piece to a sail by a longitudinal movement of the head piece relative to an edge of said sail, and means capable of association with the first named means for securing said head piece to the sail.

In testimony whereof I have affixed my signature.

LOUIS J. LARSEN.
